UNITED STATES PATENT OFFICE

CARMINE PASTELLA, OF CHARLEROI, PENNSYLVANIA

OUTLET BOX ADAPTER

Application filed May 27, 1930. Serial No. 456,218.

This invention relates broadly to outlet boxes and has more particular reference to the manner of supporting an outlet box in position in the ceiling of a room, the primary object of the invention being in the provision of an adapter for retaining the outlet box against movement relative to, and in registry with the opening in the ceiling.

A still further object of the invention is to provide an adapter which can be readily and easily associated with the outlet box, and further an adapter which is simple in construction, practical, thoroughly reliable, and efficient in operation, and otherwise well adapted to the purpose designed.

Other objects and advantages of the invention will become apparent during a study of the following description taken in connection with the accompanying drawings, wherein:—

Figure 1 is a fragmentary detail sectional view taken through a ceiling and an outlet box arranged therein for more clearly illustrating the application of the invention.

Fig. 2 is a plan view of the adapter.

Fig. 3 is an edge elevational view thereof.

Fig. 4 is a bottom plan view of the outlet box, the adapter associated therewith, being indicated in dotted lines.

With reference more in detail to the drawings, it will be seen that C designates a ceiling provided with a suitable opening O. Arranged beneath the flooring and having its lower end portion fitting conformably with in the opening O is a conventional type of outlet box B such as is used for suspending electrical fixtures from the ceiling.

A conventional type of offset hanger bar H is provided in the usual manner for supporting the outlet box B, and it will be noted that the end of the offset hanger bar H rests on the ceiling C between the floor joists J.

As before stated, the outlet box B is of conventional construction embodying the usual apertured top to which is secured in the usual manner one end of the cable E. Depending from the top of the box is the usual stud S for suspending the fixture from the outlet box. At its lower end and extending inwardly from the peripheral wall thereof,

the outlet box is provided with a pair of diametrically opposite apertured ears L.

The ears L are disposed in substantially the same plane with the under face of the ceiling C.

My improved adapter comprises an annular plate 5 having extending upwardly from one face thereof and arranged thereon in circumferentially spaced relation penetrating and retaining prongs 12 adapted to extend upwardly through the ceiling, when the plate 5 is arranged in position on the ceiling, the diameter of the aperture of the plate 5 being substantially the same as the diameter of the outlet box B for registry with the opening O.

The plate 5 on its inner circumferential edge has extending inwardly from said edge in diametrically opposed relation, lugs 6 and 7 provided with pairs of openings 8, 9. Securing the plate 5, to the box B, a suitable screw 10 is threaded through one of the openings 8 and thru the ear L with which said opening registers, while a second screw 11 is threaded through one of the openings 9 registering with the remaining ear L.

As suggested in Fig. 4, the openings 8 and 9 registering with the ears L are in diagonal relation, that is to say, on opposite sides of an imaginary line drawn through the diameter of the plate 5 and bisecting the ears 6 and 7.

From a study of Fig. 1, and in using an adapter embodied in the features of the present invention, the bar hanger H need not be anchored or nailed to, but may merely rest on the lathes, the adapter functioning to hold the outlet box against movement and in position within the opening.

A distinct advantage of an adapter of this character is that under ordinary circumstances it was necessary to take a piece of flooring out, directly over the opening in the ceiling where the outlet box was to be placed, but in using the adapter, the floor can now be taken up as far as five feet away from the opening over which the outlet box is to be placed, that is of course provided that the opening in the flooring be in the space between the floor joists, it being

apparent that the outlet box may be readily "fished" over the opening in the ceiling and can be later adjusted after being moved in position in registry with the opening.

It is thought that from the foregoing description, taken in connection with the accompanying drawings, a clear understanding of the construction, utility, and advantages of an invention of this character will 10 be had by those skilled in the art without a more detailed description thereof.

Even though I have herein shown and described the preferred embodiment of my invention, it is to be understood that the same 15 is susceptible to changes in size, shape, materials used, and other details of construction coming within the spirit of the invention as herein described, and within the scope of the appended claim.

20 Having thus described my invention what I claim as new is:

An outlet box having in combination a pair 25 of diametrically opposed apertured ears extending inwardly from the peripheral wall thereof at the open end of the box, an adapter plate provided with an opening in registry with the open end of the outlet box, inwardly directed apertured lugs on said plate for registry with said ears, bolts passing 30 through the registering openings of said lugs and said ears for securing the plate to said box, said adapter plate adapted to be disposed in abutting relation with the ceiling about the opening in the ceiling accommodat- 35 ing the outlet box, penetrating prongs integral with and extending from one face of said plate and adapted to be driven into the ceiling.

In testimony whereof I affix my signature.

40 CARMINE PASTELLA.
